TOY

Harold D. Allen, East Hampton, Conn., assignor
to The Gong Bell Manufacturing Company,
East Hampton, Conn., a corporation of Con-
necticut

Application March 8, 1939, Serial No. 260,533

6 Claims. (Cl. 46—105)

My invention relates to improvements in toys, more particularly to toy animals, toy characters and the like.

One of the objects of my invention is to provide a novel mechanism adapted to impart to the toy the life-like movements of the animal or character that it is intended to simulate.

Another object of my invention is to provide a toy of novel construction, which will impart to the leg members of the toy, when the toy is actuated, a combined reciprocating and rocking motion simulating the natural movement of the imitated animal.

Another object of my invention is to provide an improved toy of simple and durable construction and economical to manufacture.

Other objects of my invention will be set forth in the following description and drawing, which illustrate a preferred embodiment thereof, it being understood that the above statement of the objects of my invention is intended generally to explain the same without limiting it in any manner.

Fig. 1 represents a side elevation of a toy dog embodying the invention.

Fig. 2 is a sectional view on the line 2—2 of Fig. 3.

Fig. 3 is a bottom plan view.

Fig. 4 is a sectional view on the line 4—4 of Fig. 1.

Fig. 5 is a diagrammatic view, showing several positions of the front leg members.

Fig. 6 is a diagrammatic view, showing several positions of the hind leg members.

Referring to the drawing, the toy comprises a body member 1 made from wood or any other suitable material. Although the body member 1 simulates in outline a dog, it is to be understood that my invention is not to be limited to the particular animal illustrated. It may be applied to any toy animal, toy character or the like.

As shown in Fig. 3, axles 18 and 19 are mounted to extend laterally through the front and rear portions respectively of body member 1. Axle 19 has front wheels 16 and 17 concentrically mounted on the ends thereof. Axle 18 has similarly mounted thereon wheels 14 and 15.

As clearly shown in Fig. 1, each wheel has movably mounted thereon a generally J-shaped leg member. More specifically, wheel 16 carries leg member 4; wheel 17, leg member 5; wheel 14, leg member 2; and wheel 15, leg member 3. Leg members 4 and 5, which constitute the front legs of the toy animal are identical in

construction and contour. Leg members 2 and 3 which constitute the rear or hind legs of the toy animal are identical in construction with front leg members 4 and 5, but differ somewhat in shape and design from said front leg members. 5 Rear leg members 2 and 3 are somewhat squat and short in appearance so as to conform as much as possible to the hind legs of the depicted animal. Said leg members 2, 3, 4 and 5 may be made from metal, cardboard, fibre board or any 10 other sufficiently stiff material.

Each leg member is formed with a lower slot and an upper slot. More specifically, leg member 4 is formed with upper slot 12 and lower slot 13; 15 leg member 5, upper slot 12a and lower slot 13a; leg member 2, upper slot 10 and lower slot 11; and leg member 3, upper slot 10a and lower slot 11a. The function these slots perform in the operation of the toy will be hereinafter explained.

As shown in Fig. 1, pin 9 is eccentrically 20 mounted on wheel 16. The shank of said pin 9 passes through slot 13 of leg member 4, so that said pin 9 slides relative to said slot. Likewise, there is also eccentrically mounted on wheel 17, pin 9a, which slides relative to slot 13a. It should 25 be noted that pin 9 is mounted on wheel 16 diametrically opposed to pin 9a on wheel 17, so that irrespective of the positions leg members 4 and 5 may assume while in motion, said pins 9 and 9a will always be diametrically opposed to each 30 other.

As clearly illustrated in Fig. 4, spacers 8b and 8c are rotatably and concentrically mounted on both sides of body member 1, above wheels 16 and 17 respectively, by means of pins 8 and 8a. The 35 shanks of pins 8 and 8a pass through upper slots 12 and 12a respectively so that said slots slide along said pins. It should be noted that pins 8 and 8a are stationary while pins 9 and 9a move with wheels 16 and 17 respectively. The peripheral faces of spacers 8b and 8c abut the peripheral faces of wheels 16 and 17, thereby rotating in unison whenever wheels 16 and 17 revolve.

Referring to the rear portion of the body of the toy, pin 7 is eccentrically mounted on wheel 45 2 and pin 7a is eccentrically mounted on wheel 3, both pins being positioned diametrically opposite to each other. The shanks of pins 7 and 7a extend through slots 11 and 11a respectively and said pins slide relative to said slots. Spacers 50 6b and 6c are rotatably and concentrically mounted on both sides of body member 1 above wheels 14 and 15 respectively, by means of stationary pins 6 and 6a. The peripheral faces of spacers 6b and 6c abut the peripheral faces of 55

- wheels 14 and 15, thereby rotating in unison whenever wheels 14 and 15 revolve. The construction and operation of the rear portion of the toy is identical in all respects with the construction and operation of the front portion of the toy. However, the rear portion of the toy is provided with a noise making mechanism, the construction and operation of which will herein-after be described.
- 10 When the toy is propelled by means of string or cord S, the movements of the various leg members are as follows:
- When the toy is in the position shown in Fig. 1, leg member 5 is in advance of leg member 4.
- 15 As wheels 16 and 17 revolve, a combined reciprocating and rocking motion is imparted to leg members 4 and 5, thus causing a series of alternate movements of the leg members, thereby simulating the natural movements of the imitated animal. As wheels 16 and 17 revolve, pins 9 and 9a ride in their respective slots 13 and 13a. Pins 8 and 8a being stationary, slots 12 and 12a slide along the shanks of said pins.
- 20 As all four wheels 14, 15, 16 and 17 revolve, spacers 6b, 6c, 8b and 8c will revolve on the shanks of their respective pins 6, 6a, 8 and 8a. This action imparts an interesting motion to the leg members of the toy or character.
- 25 When pin 9 is at its lowest point, said pin will abut the lower end of slot 13 and pin 8 will abut the uppermost end of slot 12; pin 9a on wheel 17 will therefore be located at its highest point and will therefore abut the uppermost end of slot 13a and pin 8a will abut the lower end of slot 12a.
- 30 As wheel 16 revolves, each time pin 9 comes in contact with the uppermost end of slot 13, leg member 4 will be raised and it is because of this construction that there is imparted to each leg member a series of combined reciprocating and rocking movements which simulate the walking animal. The operation of all four wheels and their respective leg members is the same.
- 35 It will be noted that slots 13 and 13a, 11 and 11a are about double the length of slots 12 and 12a, 10 and 10a respectively. All the slots are parallel with each other and are formed so as to be inclined to the peripheries of each wheel and spacer. The length of each of the lower slots 13, 13a, 11, 11a is approximately equal to the radius of wheels 16, 17, 14 and 15.
- 40 As a source of further amusement, a noise-producing mechanism is mounted upon the rear and bottom portions of body member 1. Briefly, the underside of the rear portion of body member 1 is grooved to form a channel 20. A ratchet member 33 is mounted upon axle 18 so that it will rotate within channel 20. It will be noted that axle 18 is square in cross-section except at its ends. A resilient leaf spring 21 is secured at one end by means of a staple 22 to the underside of body member 1. The free end of said spring 21 contacts the teeth of ratchet member 23 as the latter rotates when the rear wheels 14 and 15 revolve, thus producing a series of noises. Any noise-producing mechanism may be combined with my invention and I therefore do not wish to be limited to the particular noise-producing mechanism described herein.

While I have shown and described a preferred embodiment of my invention, it is obvious that various alterations and modifications may be made in construction and arrangement of parts without departing from its spirit.

For example, spacers 8b, 8c, 6b and 6c may be omitted and pins of sufficient length may be employed.

The shape and contour of the leg members will of course depend on the type of animal or character to be imitated.

My invention is not to be limited to a four wheel toy and can be readily adapted and utilized for a two or three wheel toy.

I claim:

1. A toy comprising a body member simulating an animal or the like, wheels upon which said body member is mounted, leg members having a lower and upper slot formed therein, each of said leg members being movably mounted upon each of said wheels, a first pin passing through said upper slot and into said body, a second pin eccentrically mounted upon each wheel, each of said second pins cooperating with the lower slots of each leg member to impart to said leg member a combined reciprocating and rocking motion, when the wheels are revolved.

2. A toy as claimed in claim 1 in which the slots of each leg member are parallel to each other and inclined to the peripheries of the wheels.

3. A toy as claimed in claim 1, in which noise producing means is associated therewith.

4. A toy comprising a figure, wheels upon which said figure is supported, leg members having an upper and lower slot formed therein movably mounted upon said wheels, a pin eccentrically mounted upon each wheel, each of said pins being located diametrically opposite to the corresponding pin and being movably connected to the lower slot of each leg member, a stationary pin secured to the body member above each wheel and connected to the upper slot of each leg member, each of the pins cooperating with their respective slots to impart a series of alternate movements to each of said leg members, when the wheels of the toy revolve.

5. A toy comprising a figure, wheels upon which said figure is mounted, leg members having an upper and lower slot formed therein movably mounted upon said wheels, a pin eccentrically mounted upon each wheel, each of said pins extending through the lower slot of each leg member, a stationary pin secured to the figure above each wheel and extending through the upper slot of each leg member, a spacer rotatably mounted on each of said stationary pins, the peripheral faces of said spacers and the peripheral faces of said wheels abutting each other, each of the pins cooperating with their respective slots to impart a series of alternate movements to each leg.

6. A toy as claimed in claim 5 in which the pin eccentrically mounted upon each wheel is located diametrically opposite to the pin on the corresponding wheel.

HAROLD D. ALLEN.
